TOY HORSE AND WAGON

Robert S. Chalmers, Southington, Conn.

Application May 22, 1957, Serial No. 46,279

Term of patent 3½ years

(Cl. D34—15)

The single figure on the drawing is a perspective view of the toy horse and wagon showing my new design.

The opposite side of the toy horse and wagon is substantially the same as that shown in the figure.

I claim:

The ornamental design for a toy horse and wagon, substantially as shown and described.
